CLAIM

The ornamental design for balanced light for drafting tables, as shown and described.

DESCRIPTION

FIG. 1 is a front perspective view of a balanced light for drafting tables or the like showing my new design;
FIG. 2 is a rear perspective view thereof;
FIG. 3 is a fragmentary top plan view of the balanced light for drafting tables or the like on an enlarged scale, the support being fragmentarily shown for convenience of illustration;

FIG. 4 is a fragmentary side elevational view thereof;
FIG. 5 is a fragmentary bottom plan view thereof; and
FIGS. 6 and 7 are rear, front and elevational views of the lamp head on an enlarged scale, the yoke and support being omitted for convenience of illustration.
